SHOE PASTING PRESS

Erich Priess, Freital, Dresden, Germany

Application January 31, 1939, Serial No. 253,846
In Germany January 31, 1938

4 Claims. (Cl. 12—51)

The method of repairing boots and shoes with the aid of a paste as now successfully practised necessitates specially designed presses permitting to clamp fast the work-piece very securely and in 5 such a manner that it is accessible on all sides and can resist the pressures to which it is subjected while the repair is being effected. As regards, for instance, the pasting on of soles there is required for this sort of work a stationary 10 support upon which the boot or shoe is to be shoved and which is provided with clamping bows, belts, and the like for holding a pressure-exerting or more precisely, pressure-transmitting cushion (termed "press-cushion" in the following 15 parts of this specification) which is to be pressed onto the sole lying upon the boot or shoe. A press of this design is, however, not suited for the pasting on of patches, toe-caps or leg parts and can be used only for one of these several 20 purposes. Owing thereto, there is, for instance, the press cushion requisite for pressing on the substitute boot or shoe part to be pasted on arranged at a bow to which it can be attached, together with a threaded adjusting spindle, in several 25 positions, but as said bow is not sufficiently resistible, the press cushion cannot be subjected to a sufficiently high pressure in the several positions to which it must be adjusted for the carrying out of the respective work.

20 Presses having a stationary base plate, and a cushion carrier firmly attached thereto and permitting of being tightened up together with the appertaining adjusting spindle, are likewise suited only for the subsequent pasting on of substitute boot or shoe parts or of heels. It has been suggested to make the last carrier turnable so as to render it possible to adjust the work-piece with respect to the member effecting the pressure in such a manner that it is accessible on all 30 sides, and it has, further, already been suggested to make said carrier also adjustable, or shiftable respectively; but constructions of this kind necessitate long jib arms which do not make it possible to exert a sufficiently strong pressure 35 during the pasting-on operation, except, the entire frame be extraordinarily clumsy, but a frame of such a type is not suited for small repair work, furthermore too expensive, too circumstantial and also too bulky.

40 The present invention relates to a simple, small-size boot and shoe pasting press for pasting on patches and for general repair-work which is distinguished by the features that the press-cushion is guided on an arm turnably attached 45 to the base plate of the press and being fixable

5 at said plate. If, besides, an exchangeable abutment member is provided at the base plate, the boot or shoe to be repaired can be clamped fast in any desired position with respect of the press-cushion and to the abutment member and is accessible on all sides, especially also at the leg, so as to permit the pasting-on of patches, as well as of soles and heels. An especially important feature of this improved press is, furthermore, that it is extremely rigid and still in itself so 10 that the place where a patch or the like is to be pasted-on can be subjected to a pressure of any requisite magnitude and the repair can be of an excellent quality highly satisfying the wearer of the respective boot or shoe.

15 The invention is illustrated diagrammatically and by way of example on the accompanying drawing in which

20 Figure 1 is a vertical section through a boot and shoe pasting press designed according to this invention, with a boot to be repaired inserted, the section being seen in the direction from the toe portion of the heel.

25 Figure 2 is a side-view of the parts shown in Fig. 1.

30 Figure 3 is a view similar to Fig. 2, but showing the boot in another position and the vertical bow (2) of Figs 1 and 2 being turned down into horizontal position; and

35 Figure 4 is a view similar to Fig. 3, but showing the boot again in another position.

40 On the drawing, 1 denotes a base-plate to which is hinged a bow 2 by means of bolts 3. Although I have shown an actual U-shaped bow comprising an arm on its right-hand side and an arm on its left-hand side, I wish it to be understood that, under circumstances, one arm may suffice, but I prefer the constructional form shown on account of its greater rigidity. The bow can be secured in its vertical position, as well as in its horizontal position, by means of pins or bolts 4 engaging suitably located bores, as shown in Figs. 2 and 3.

45 In the bow is guided a shiftable spindle 6, to the lower end of which the press cushion 9 is attached. A helical compressive spring 8 surrounding the upper end of said spindle tends to hold the spindle with the press cushion in lifted position, but these parts can be fixed in any 50 position therebelow by any suitable means, for instance a clamping device 5, 7 or any other suitable contrivance of known design. On the top of the spindle, above said spring, is a knob 11, with the aid of which the press cushion can be 55 depressed upon the boot or shoe portion where

a patch is to be pasted on or any other repair is to be made, and thereafter the cushion is fixed in this position by means of said device 5, 7 or its equivalent. When the work has been finished, 5 the device 5, 7 is released, whereupon the spring will lift the cushion off from the work-piece.

Also the press-cushion 9 can be of any desired 10 design; it may, for instance, be completely stuffed-out or may be filled with a liquid or a gas and 15 may be equipped with a member permitting pumping up the cushion if necessary. As a rule, however, the cushion shall be completely closed and retain its filling permanently.

The cushion is connected with the spindle 6 by 15 means of a plate 6^a which is provided with a means for exerting an additional pressure upon the cushion after it has been depressed by the intermediary of the spindle and secured in that position by the clamping device 5, 7. In the 20 example shown said means consists of a plate 9^b attached to the bottom surface of the plate 6^a and being loosely hinged thereto at one end (9^c), whereas the other end is subject to the action of an eccentric 9^e supported upon the plate 6^a. 25 When the grip (shown in dotted lines in Fig. 1) pertaining to the eccentric is turned from its right-hand position (Fig. 1) to its left-hand position, the eccentric proper will depress the plate 9^b and exert thereby the additional pressure upon 30 the press-cushion 9.

In operation, when a boot or shoe is to be repaired, the respective work-piece is placed upon the base plate 1, as, for instance, in Figs. 1 and 2, and the press-cushion is moved down upon it by 35 means of the members 11 and 6, and is pressed firmly against it, whereafter the cushion is fixed in this position by means of the clamping device 5, 7, as already described. Now the additional plate 9^b is depressed by means of the eccentric 40 9^e so as to ultimately secure the press-cushion in its position on the work-piece.

In Figs. 1 and 2 is assumed that a toe-cap is to be pasted onto the boot 12, and it is for this reason that the bow 2 and the spindle 6 are in their 45 vertical position. In order to effect a repair for instance at the rear of the heel or at a side of the same the bow with the spindle are turned into horizontal position, as in Figs. 3 and 4, and in order to give the boot (or shoe) a firm hold 50 55 also in any of these positions or in a similar position, an abutment member 10 (may be, several such members) can be attached to the base-plate 1 and be secured thereon by means of a pin 10^a provided in said plate. In Fig. 2 the abutment member 10 is in its position of rest, viz. not engaged,

whereas it is engaged in Figs. 3 and 4 in two different positions.

I claim:

1. In a boot and shoe pasting press, especially for patches and repairs, in combination, a stationary base-plate on which the boot or shoe to be pasted is placed, an arm turnably hinged to said plate, means adapted to adjust said arm to said plate in predetermined positions, a press cushion guided on said arm, means for adjusting and fixing said cushion on said arm in different positions, the hinge between said plate and said arm lying above the level of said plate, and substantially on a level with the boot or shoe to be pasted. 15

2. In a boot and shoe pasting press, especially for patches and repairs, in combination, a stationary base-plate, an arm turnably hinged to said plate, means adapted to adjust said arm to said plate in predetermined positions, a press cushion guided on said arm, means for adjusting and fixing said cushion on said arm in different positions, means for subjecting the plate with said cushion to a preliminary or initial pressure, and separate means for exerting a finishing or final pressure as an addition to the first-mentioned pressure are provided. 20 25

3. In a boot and shoe pasting press, especially for patches and repairs, in combination, a stationary base-plate, an arm turnably hinged to said plate, means adapted to adjust said arm to said plate in predetermined positions, a press cushion guided on said arm, means for adjusting and fixing said cushion on said arm in different positions, means for subjecting the press-cushion to a preliminary or initial pressure comprising a vertically movable plate fitting upon the cushion, and the means for subjecting the cushion to a finishing or final pressure comprising a separately movable plate arranged at the bottom of the first-mentioned plate, and means supported on this latter and adapted to exert a downwardly directed pressure. 30 35 40

4. In a boot and shoe pasting press, especially for patches and repairs, in combination, a stationary base-plate, an arm turnably hinged to said plate, means adapted to adjust said arm to said plate in predetermined positions, a press cushion guided on said arm, means for adjusting and fixing said cushion on said arm in different positions, members adapted to serve as abutments for the work-piece attached to the base-plate and adapted to be arranged thereon and secured thereto in several positions. 45 50 55
